UNITED STATES PATENT OFFICE

WARREN DELOSS MARTIN, OF PORT BLAKELY, WASHINGTON

BOAT FOR SPEED

Application filed November 5, 1932. Serial No. 641,331.

The invention relates to the propulsion of a boat by means of two endless air belts, one on either side of the keel. These belts also serve as the bottom of the boat and nothing else touches the water but the keel. More than two belts may be used on larger boats.

In the accompanying drawings Fig. 1 is a plan view of the boat as it appears with the deck removed. Fig. 2 is an elevation 10 section thru line A—A of Fig. 1. Fig. 3 is a side elevation view of the boat showing how the sides cover the belt and shows the water line 7.

Fig. 4 is a perspective view of the main belt 15 with pockets. Fig. 5 is an enlarged scale perspective view of a section of the main belt. Fig. 6 is an elevation of one of the pneumatic tubes. Fig. 7 is an end view of one of the pneumatic tubes with valve.

20 In Fig. 1 the belts 1—1 are run over the front drums 2—2 and the rear drums 4—4. The drums are shown by the dotted lines. The belts are driven from the rear drums 4—4, by gears in housing 3, but may be 25 driven from either front or rear.

There are screws provided on the bearings of the shaft of the front drums at 9 for taking up the slack in the belts.

20 The rolls 5 in Fig. 2 are held in the position shown, by racks 8 to allow the belts to enter the water gradually and leave the water gradually. Each belt 1—1 consists of a main section 9, as shown in Fig. 5, to which are attached tube pockets 10 into which tubes 35 11 are inserted. These tubes are inflated with air through a suitable valve 12.

Air tanks 6 are used to insure safety and will also be placed between the rolls 5 and the upper belt.

40 I claim:

1. A propelling device for a boat, comprising a driving drum, a driven drum, an endless flexible belt mounted on said drums, pockets of flexible material on said belt and valve means for inflating said pockets to support the boat in water.

2. A propelling device for a boat having a hull, comprising a plurality of shafts journaled to lie crosswise of the longitudinal axis of said hull, driving and driven drums

55 mounted on some of said shafts, an endless flexible belt mounted on said drums, and belt guiding rolls mounted on other of said shafts and at a lower level than said drum supporting shafts, inflatable pockets of flexible material on said belt and valve means for inflating said pockets.

60 WARREN DELOSS MARTIN.
